BENDING MACHINE

Daniel A. Lyons, Los Angeles, Calif., assignor to
 Consolidated Steel Corporation, Ltd., Los Angeles, Calif., a corporation of California

Application August 23, 1937, Serial No. 160,359

6 Claims. (Cl. 153—15)

This invention relates to machines for bending elongated members, such as rods, strips, pipes, etc., and has as a broad object to provide a power-actuated bending machine that is simple and inexpensive to construct and operate.

A more specific object is to provide a bending machine adapted to be operated by compressed air, steam or other fluid under pressure with maximum economy of the fluid employed.

10 Still another specific object is to provide a bending machine having a simple and effective structure for quickly and accurately adjusting the range of movement of the movable bending element.

15 The manner in which the foregoing objects are achieved, and the essential features of the invention, will now be explained by describing in detail a particular embodiment of the invention with reference to the drawings.

20 In the drawings:

Fig. 1 is a plan view of a bending machine in accordance with the invention;

Fig. 2 is a front elevational view of the machine shown in Fig. 1, with portions broken away to

25 show the construction;

Fig. 3 is a detail vertical sectional view, taken substantially in the plane III—III of Fig. 1;

Fig. 4 is a detail sectional view, taken substantially in the plane IV—IV of Fig. 1; and

30 Fig. 5 is a perspective view of a stop element employed in the machine.

Referring first to Figs. 1 and 2, the bending machine therein disclosed comprises a frame including a top plate 1 constituting a table, a bottom plate 2 and an intermediate plate 3 positioned in spaced relationship between plates 1 and 2. The bottom plate 2 is supported from a flooring by a pair of I-beams 4 and 5, respectively. The intermediate plate 3 is supported on the bottom plate 2 in spaced relation thereabove by a plurality of channel section members 6, 7, 8 and 9, and the top plate 1 is supported from the intermediate plate 3 in spaced relation thereabove by channel section members 10, 11, 12, 13 and 14, the members 10, 11, 12 and 14 being positioned immediately above the members 6, 7, 8 and 9, respectively. All of the parts described may be rigidly interconnected together by welding into a strong frame. Positioned above the top plate 1 and rotatable in a horizontal plane thereabove is a bending arm 15 having a shaft 16 projecting upwardly therefrom and positioned coaxially with the axis of rotation of the arm 15. The arm is also provided with a plurality of spaced apertures 17, any one of which is adapted to receive a pin

18 supporting a roller 19 adapted to engage and bend a rod or other elongated member to be bent in the machine. On the front and rear edges of the top plate 1 constituting the table of the machine, there are mounted relatively rigid supporting members 20 and 21, respectively, for supporting a rod laid thereacross in a suitable plane to be intercepted by the shaft 16 and roller 19 of arm 15. The member 20 is provided with a plurality of spaced apart holes 22 any one of which is adapted to receive a pin, and the member 21 is also provided with holes 23 any one of which is adapted to receive an upstanding pin, which pins may constitute fixed guide means for supporting a rod being bent.

I also preferably provide another rigid guide supporting member 25 positioned above the top plate 1 and between the edges of the plate 1. The upper surfaces of the members 20, 21 and 25 preferably all lie substantially in the plane of the upper surface of arm 15. The member 25 is provided with a plurality of holes 26 therein, any one of which is adapted to receive a pin 27 supporting a roller 28.

One method of bending a rod with the machine 25 described is shown in Fig. 1, in which a rod 29 to be bent is laid across the members 20, 25 and 21 against the stationary roller 28 and the shaft 16 on arm 15. Arm 15 normally extends straight to the left (with reference to Fig. 1). The machine is then actuated in a manner to be described later, causing the arm 15 to rotate about the axis of the shaft 16 in a counterclockwise direction, thereby causing the roller 19 to intercept the rod 29 and bend it about the shaft 16, as 35 shown in dotted lines at 29a. If only a single bend were to be placed in the rod, there would be no stop means inserted in any of the holes 23 in member 21, and the front end of the rod would swing around as far as necessary depending upon 40 the angle of the bend placed in the rod at its point of contact with the shaft 16. However, with the particular setup of Fig. 1, an arrangement is shown for placing a double bend in the rod 29. To this end a rigid bar or channel member 35 is laid across the table on the members 20 and 21 and supported against horizontal movement to the right by a pin 36 inserted in one of the holes 22 in member 20 and a pin 37 inserted in one of the holes 23 in the member 21. Therefore, as the front end of the bar swings around the shaft 16, it contacts the stop member 35 and is thereafter bent around the roller 19, as indicated at 29b, the motion continuing until the rod at bend 29b contacts the stop member 35, under 50 55

which condition the resistance afforded to further movement of the arm 15 by the stop member 35 stops the arm. The net result of the bending operation described is to form the rod 29 into two parallel sections interconnected by a diagonally extending section.

If desired, the stop member 35 can be removed and a double bend placed in the bar 29 by merely inserting the pin 37 in a suitable aperture 23 in member 21, bar 29 then bearing directly against the pin 37 instead of against the stop bar 35. Under such conditions the angle of the bends placed in the rods is determined by the extent of movement of the arm 15, and such movement is limited by a stop mechanism associated with the arm, to be described later.

Referring now to the mechanism for rotating the arm 15, the arm is rigidly attached to the shaft 16 which extends a substantial distance below the arm and is journaled in an upper bushing 40 positioned within an upper bearing member 41, (Fig. 3) supported by the upper plate 1 and the intermediate plate 3, and in a lower bushing 42 in a lower bearing member 43 supported by the lower plate member 2.

Shaft 16 has keyed thereto at a point thereon intermediate the lower bearing bushing 42 and the upper bearing bushing 40, a pinion 44 which meshes with a rack 45 extending horizontally between plates 2 and 3. A roller 46, mounted on a shaft 47 supported between the plates 2 and 3, bears against the back face of the rack 45 to maintain the rack in positive engagement with pinion 44 at all times.

Referring now to Figs. 1 and 2, the rack 45 is rigidly connected at its right end to a relatively large piston rod 48 extending from the left end of a cylinder 49, the rod 48 connecting at its inner end to a piston 50 mounted within and sealing with the walls of the cylinder 49. A suitable stuffing box 51 is provided on the left end of the cylinder 49 for sealing about the large piston rod 48. Pipes 52 and 53, respectively, lead from the opposite ends of the cylinder 49 through a control valve 54 which also connects to a pipe 55 leading to a source of fluid under pressure, such as compressed air or steam. The valve 54 is a valve of conventional construction which may be actuated into a plurality of positions to connect either pipe 52 or pipe 53 with the pressure fluid supply pipe 55 and simultaneously exhaust the other pipe 53 or 52 to the atmosphere or to an exhaust line. It will be obvious that by admitting pressure fluid to pipe 53 and venting the pipe 52, fluid pressure will be admitted to the right end of cylinder 49 to move the piston 50, the piston rod 48, and the rack 45 to the left, thereby rotating the shaft 16 and the arm 15 thereon in counter-clockwise direction, whereas, by admitting pressure fluid from pipe 55 to pipe 52 and venting the pipe 53, the piston 50, piston rod 48 and rack 45 will be moved to the right to restore the shaft 16 and arm 15 to normal position. Since it is intended that the arm 15 perform work in bending a rod only when moved in counter-clockwise direction, it is necessary to apply substantial force to the arm 15 when rotating it in counter-clockwise direction, whereas the only force required to retract the arm back to normal position is that necessary to overcome the friction of the parts. It is for this reason that the piston rod 48 is made of relatively large diameter so that the effective area of the left face of the piston 50 is relatively small and the displacement volume of the cylinder on the left side

of the piston 50 is relatively small, and only a relatively small amount of fluid pressure is consumed in moving the piston from left to right position. On the other hand, the effective area of the right end of the piston 50 is the full area of the cylinder, thereby providing the necessary surface to develop a powerful force for movement to the left in response to fluid admitted to the cylinder under moderate pressure.

It has been previously mentioned that it is often desirable to determine the extent of a bend placed in a rod by limiting the angle of rotation of the arm 15 by an adjustable stop means incorporated in the mechanism for actuating the arm. This mechanism comprises a stop member 60, (Fig. 4) adapted to intercept a cross head 61 on the left end of the rack 45 and thereby limit the length of the stroke of the rack. Obviously limitation of the stroke of the rack 45 limits the arc of rotation of the shaft 16 and the arm 15. The cross head 61 is guided for longitudinal movement by a slotted tubular stationary member 62 supported at opposite ends by the channel member 7, and the channel member 6, the ends of the cross head 61 being slidably fitted within the slots in tube 62 and the channel member 7 having a suitable aperture therein for receiving the end of the member 62 and passing the rack 45. The stop member 60 comprises a tubular member of internal diameter slightly larger than the external diameter of the guide tube 62 so as to slide freely therewith. The member 60 has diametrically opposite cuts in its right end at spaced intervals thereabout to provide three sets of abutting faces adapted to contact the cross head 61.

Thus referring to Fig. 5, there are a pair of diametrically opposite high faces 63, a pair of diametrically opposite low faces 64, a pair of diametrically opposite intermediate faces 65. Each of the faces extends circumferentially through an angle of 60° so that by rotating member 60 through a total angle of 160° any one of the three sets of faces 63, 64 and 65 may be presented to the cross bar 61. Such rotation of the stop member 60 may be effected by a handwheel 66 mounted on a shaft 67 having a sprocket wheel 68 keyed thereto, which sprocket wheel is coupled by a chain 69 to a sprocket wheel 70 on the member 60. Rotation of the handwheel 66 permits three adjustments for large variations in the stroke of the rack 45 and the arm 15. However, in accordance with the present invention, I provide further means for effecting adjustment of the longitudinal position of the stop member 60. To this end there is provided a cross head 71 extending across through the slots in the tubular member 62 back of the stop member 60 and coupled thereto for simultaneous longitudinal movement, but in such way as to permit rotation of member 60 without rotation of the cross head 71. Thus the member 60 may be provided with an annular groove 72 therein adapted to receive the inwardly projecting ends of fingers 73 secured to the ends of cross head 71. Cross head 71 is provided with a threaded central aperture which receives the threaded inner end of a shaft 74 which is rotatably mounted in a bearing member 75 rigidly secured to the channel member 6. Shaft 74 has mounted on its rear end a handwheel 76 which bears against the end of bearing member 75 and limits inward movement of the shaft 74. A collar 77 on the shaft 74 bears against the right end of the bearing member 75 and prevents outward movement of the shaft.

It will be apparent that the shaft 74 restrains the cross head 71 and the stop member 60 from longitudinal movement in response to abutment of the cross head 61 on the rack 45 against the member 60, but that longitudinal adjustment of the stop member 60 may be had by rotating the handwheel 76.

When it is desired to move the arm 15 through a definite arc, the handwheel 66 is first rotated to rotate the sleeve 60 into such position as to align one of the three sets of faces 63, 64 and 65 with the cross head 61, which will limit movement of the rack 45 so as to stop the arm 15 in approximately the position desired. Final accurate adjustment of the limiting position of the arm 15 can then be had by rotating the handwheel 76 to adjust the stop member 60 longitudinally by the action of the screw 74a.

The machine as described can be operated very rapidly with relatively small consumption of compressed air or steam by virtue of the fact that the limiting position of the arm is effectively fixed irrespective of the pressure of fluid employed to move the piston. Therefore the pressure can be sufficiently high to move the arm very rapidly and positively through its stroke. At the same time full pressure fluid can be admitted to restore the arm to normal position quickly without waste of fluid by virtue of the small area of the back face of the piston.

Obviously many minor variations can be made in the particular embodiment of the invention disclosed, which has been described in detail for purposes of explaining the invention; the invention is therefore to be limited only to the extent set forth in the appended claims.

I claim:

1. A shaping machine comprising fixed members for engaging a workpiece, a movable member for engaging a workpiece at a point spaced therealong from said fixed members, means for moving said movable member through an adjustable distance comprising an oscillatable member, and means for oscillating it, said oscillating member having a stop-engaging member thereon, a stop member in the path of movement of said stop-engaging member, said stop member having a plurality of faces thereon spaced from each other in the direction of movement of said oscillatory member, means for moving said stop member in a plane perpendicular to the path of movement of said oscillating member for selectively bringing different ones of said faces into the path of movement of said stop-engaging member, and means for restraining said stop member against longitudinal movement by said stop-engaging member.

2. A shaping machine of the type described comprising fixed members for engaging a workpiece, a movable member for engaging a workpiece at a point spaced therealong from said fixed members, means for moving said movable member to shape a workpiece, and means for adjustably limiting the distance through which the

movable member moves comprising: a stop-engaging member connected to said movable member for movement therewith, a stop member mounted in the path of movement of said stop-engaging member, said stop member having a plurality of faces thereon spaced from each other in the direction of movement of said stop-engaging member, means for moving said stop member in a plane perpendicular to the path of movement of said stop-engaging member for selectively bringing different ones of said faces into the path of movement of said stop-engaging member, and means for moving said stop member directly toward and away from said stop-engaging member by small increments.

3. A shaping machine of the type described comprising fixed members for engaging a workpiece, a movable member for engaging a workpiece at a point spaced therealong from said fixed members, means for moving said movable member to shape a workpiece, and means for adjustably limiting the distance through which the movable member moves comprising: a stop-engaging member connected to said movable member for movement therewith, a stop member comprising a tubular member positioned in the path of movement of said stop-engaging member, said tubular member having a plurality of circumferentially spaced, stepped faces on said one end thereof, and means supporting said tubular member against longitudinal and radial movement while permitting rotary adjustment thereof to present different ones of said stepped faces to said stop-engaging member.

4. A shaping machine as described in claim 3, in which said means for supporting said tubular member comprises a stationary tubular guide coaxial with and slidably engaging said tubular member.

5. A shaping machine as described in claim 3, in which said means for supporting said tubular member comprises a stationary tubular guide coaxial with and positioned within said tubular member for slidably supporting the latter for rotary and longitudinal motion thereon, said guide having longitudinal slots therein and said stop-engaging member comprising a cross head extending through said slots.

6. A shaping machine as described in claim 3, in which said means for supporting said tubular member comprises a stationary tubular guide coaxial with and positioned within said tubular member for slidably supporting the latter for rotary and longitudinal motion thereon, said guide having longitudinal slots therein and said stop-engaging member comprising a cross head extending through said slots, a second cross head extending through said slots back of said tubular member and engaging the rear end of said tubular member for longitudinal movement therewith, and means for adjustably anchoring said second cross head against longitudinal movement.

DANIEL A. LYONS.
